UNITED STATES PATENT OFFICE

1,975,561

AUTOMATIC PRESSURE REGULATOR FOR
VACUUM DISCHARGE TUBESMarshall N. States, Evanston, Ill., assignor to
Central Scientific Company, a corporation of
Illinois

Application February 1, 1932, Serial No. 590,068

22 Claims. (Cl. 176—125)

The beautiful phenomena attending the discharge between well spaced electrodes as the air pressure in the surrounding space is reduced can be obtained by connecting a static machine, 5 or induction coil, across electrodes in the respective ends of a long discharge tube and connecting the interior of the tube with a modern vacuum pumping outfit.

When the pressure within the tube is at or 10 near atmospheric no discharge will pass between the electrodes, nor will the air become visibly conducting until the pressure is very much reduced. At about one-sixth of an atmosphere (10 to 15 centimeters of mercury) bluish threads of 15 light will trickle along the walls of the tube accompanied by a crackling sound, but it will be difficult to tell the anode from the cathode.

As the pressure is lowered the threads of light 20 will thicken and appear to travel mostly through the air until, at length, a vivid red glow will fill the central cross sectional part of the tube from the anode to a faintly lighted area near the cathode, which area marks the beginning of the Faraday dark space, so called.

25 The red glow, called the positive column, will develop into distinct disks of red glow spaced by minute dark disks. The Faraday dark space will expand and travel toward the anode followed by a light known as the cathode glow, which 30 extends from a velvet glow on the cathode. The positive column all but recedes into the anode and a fluorescent glow spreads over the walls of the tube. The electric resistance which has decreased 35 with the air pressure will now begin to rise, the colors will fade, and the visible phenomena end as the vacuum becomes hard.

The transition of the phenomena is more rapid 40 than even this sketchy description indicates, and the entire period is much too brief for either scientific study or entertainment. Repetition is necessary, and it has heretofore been effected by manually letting the vacuum down, which ever included the human errors, distracted the students, or the customers, or the observers, and in many 45 appropriate uses of the apparatus has added the prohibitive cost of an attendant.

The principal object of this invention is to 50 effect automatic repetition of the phenomena at selected intervals, thereby increasing their pedagogical value and rendering their attractiveness available for entertainment and advertising.

55 Further objects and advantages of this invention will be revealed as the disclosure proceeds and the description is read in connection with the accompanying drawing, in which

Fig. 1 is a diagram of a selected discharge tube vacuum pump and induction coil connected to produce the phenomena described, and with an attachment made according to this invention for automatically letting down the vacuum when it 60 becomes hard and thereby initiating a repetition of the cycle of operations;

Fig. 2 is similar to a part of Fig. 1, showing a modification, and

Fig. 3 is an enlarged sectional view of a fragment illustrating how the mercury adheres by surface tension to the bottom of the column at one stage of the operation.

But the drawing and the specific description that follows are used to disclose and illustrate 70 the invention and not to define its scope.

The vacuum discharge tube 10 is made of soda glass, 5 feet long, $2\frac{1}{2}$ inches in diameter, and equipped with flat aluminum disk electrodes 11 and 12, 2 inches in diameter. At one side of the 75 tube and at the approximate longitudinal center a tubular arm 13, $\frac{3}{4}$ of an inch in diameter, is provided for establishing communication with the interior.

The electrodes 11 and 12 are connected with 80 an induction coil 14 yielding not less than a 3 inch spark. (The effect may be intensified by using a high tension transformer.) The arm 13 is connected by special vacuum tubing 16 and vacuum wax or stop-cock grease with what may be called, for convenience, a low pressure tube 17 having a lateral arm 18 connected in like manner with a vacuum pump 19, driven by a motor 20. The motor circuit and the electric discharge circuit are controlled by a single switch 21.

The low pressure tube 17 is enlarged at 22 to 95 form a bulb receiving the curved discharge tube 23 extending upwardly and laterally from the top of a mercury column 24 (mercury is here used to include all those well known equivalent liquids, though metallic mercury is preferred because it permits the apparatus to be made in more convenient size.) Below the bulb 22 the low pressure tube 17 resumes its normal size for a distance indicated at 25, and then is reduced to a capillary tube 26, which is return-bent at 27 and joined to the bottom of what is, for convenience, called a high pressure tube 28, surrounding the column 24 up to about the line marked B, and affording somewhat of a vessel below the line marked C. 100 The high pressure tube 28 has an upwardly inclined arm 29, which is intermediately connected by a construction 30 with a high pressure bulb 31, having an arm 32 connected with a volume chamber 33, by extending through the stopper 34. The 105 110

- stopper also carries an L-shaped tube 35 equipped with a rubber tube 36, a pinch cock 37, and a capillary tube 38, which communicates with the atmosphere or a cylinder of the gas to be studied.
- 5 The low pressure tube 17 is made of soda glass $\frac{3}{4}$ inch in diameter and the arm 18 is the same diameter. The capillary tube 26 is $\frac{1}{8}$ inch inside diameter; the mercury column 24 is $\frac{3}{8}$ inch in diameter, and $4\frac{1}{2}$ inches long between the lines 10 B and C. The high pressure tube 28 is $\frac{3}{4}$ inch in diameter, and is arranged as closely to the low pressure tube 17 as is convenient in manufacture. The arm 29, the bulb 31 and the arm 32, and the construction 30 are about in the proportion 15 shown. The volume chamber 33 is a 12 litre flask. The tube 35 is $\frac{1}{4}$ inch in diameter and the capillary 38 is $\frac{1}{2}$ inch inside diameter and 12 inches long. When the apparatus used has these dimensions, the vacuum pump should be of such capacity that it reduces the pressure in the discharge tube from about $2\frac{1}{2}$ inches of mercury to a hard vacuum in about 3 minutes.

Operation

- 25 Before starting the mercury should be at the level D with atmospheric pressure in the tubes 17 and 28. By closing the switch 21 to the position shown in Fig. 1, the motor 20 and the sparking apparatus 30 are energized. Almost immediately the mercury will rise in the low pressure tube to the line A, and there will be a corresponding drop in the high pressure tube 28. The mercury will gradually rise in the column 24 to the line B, when the relation at the bottom of the column will be substantially as illustrated in Fig. 3.
- A little additional pressure differential between the tubes 17 and 28, and the surface tension of the mercury at 39, Fig. 3, will be overcome. Air will 40 enter the bottom of the column 24 and the mercury will rise through the arm 23 and pour into the bulb 22, from which it will run down through the capillary tube 26 and replenish the bottom of the tube 28, with the result that there will be 45 a mixed column of air and mercury rising through the column 24 until the pressure in the tube 17 is brought down to about $2\frac{1}{2}$ inches of mercury, when the mercury at the bottom of the column 24 will again seal it against the admission of air 50 from the tube 28.

The phenomena described at the beginning of this specification will then take place and when the vacuum becomes hard the pressure differential between the tubes 17 and 28 will again 55 cause the mercury in the column 24 to be discharged and air will be admitted to the system to let the vacuum down and set the apparatus for another cycle of operations.

The tube 17 just above the bulb 22 is provided 60 with an interior nipple 40 bent to the side, as indicated in Fig. 1, to prevent gas rushing upwardly from entraining mercury and carrying it into the arm 18 leading to the pump or to the discharge tube 10.

65 The apparatus just described will repeat the cycle of operations at three minute intervals, or over, depending upon the constriction of tube 36 by the pinch cock 37.

Shorter intervals may be had by reducing the 70 size of the flask 33. Of course this could also be accomplished by changing the proportion of other parts, the size of speed of the pump, etc.

When the apparatus is stopped for any considerable period, there may be sufficient leaks on 75 the low pressure side of the air column to reverse

the differential and in consequence the flow. The bulb 31 will then act as a mercury trap and prevent escape to the flask 33.

In the modified form shown in Fig. 2, the low pressure tube 41, instead of enclosing the mercury column 24 is arranged along side it. This construction is not as sturdy as that shown in Fig. 1, nor is it as easy to effect the making or breaking of the mercury seal at the bottom of the column. It will, however, serve to illustrate a variant form.

The colors seen in the phenomena of the discharge tube may be varied by selecting the gas within it and the glass of which the tube is made. In nitrogen all the glow about the cathode is bright violet and the remaining color is rosy; in hydrogen blue is the dominant color, unless the tube is reduced at some area, in which case crimson would show; in carbon dioxide the light is remarkably white. Soda glass contributes to green fluorescence while lead and pyrex glasses contribute to blue.

I claim as my invention:—

1. In apparatus of the class described, comprising a vacuum discharge tube having electrodes, means for furnishing a high voltage discharge connected across the electrodes, and a vacuum pump connected with the interior of the tube in combination with automatic valve means for letting the vacuum down a substantial amount 100 each time it becomes hard, and for allowing the vacuum pump to increase the vacuum again to the hard stage after each let-down.

2. In apparatus of the class described, comprising a vacuum discharge tube having electrodes, means for furnishing a high voltage discharge connected across the electrodes, and a vacuum pump connected with the interior of the tube in combination with automatic means adapted to let the vacuum down a substantial 115 amount each time it becomes hard, and to allow the vacuum pump to increase the vacuum again to the hard stage after each let-down, comprising a column of mercury subject to the vacuum 120 in the tube above and a higher pressure below.

3. In apparatus of the class described, comprising a vacuum discharge tube having electrodes, means for furnishing a high voltage discharge connected across the electrodes, and a vacuum pump connected with the interior of the 125 tube in combination with automatic means for letting the vacuum down when it becomes hard, comprising a volume chamber having a slow leak to the atmosphere and a column of mercury subject above to the vacuum in the tube and below to the pressure in the volume chamber.

4. In apparatus of the class described, comprising a vacuum discharge tube having electrodes, means for furnishing a high voltage discharge connected across the electrodes, and a 135 vacuum pump connected with the interior of the tube in combination with automatic means for letting the vacuum down when it becomes hard, comprising a column of mercury subject to the vacuum in the tube above and a higher pressure 140 below, and means to conduct mercury from the top to the bottom of the column.

5. In apparatus of the class described, comprising a vacuum discharge tube having electrodes, means for furnishing a high voltage discharge connected across the electrodes, and a vacuum pump connected with the interior of the tube in combination with automatic means for letting the vacuum down when it becomes hard, comprising a column of mercury subject to the 145 150

- vacuum in the tube above and a higher pressure below, and means to conduct mercury from the top to the bottom of the column, including a capillary tube.
5. 6. An article of manufacture for automatically letting down the vacuum in a discharge tube comprising as a unitary structure a column adapted to receive mercury, a high pressure tube in suitable communication with the bottom of the column, a low pressure tube in communication with the top of the column, and adapted to be connected with the interior of the vacuum discharge tube, and a return tube between the low pressure tube and the bottom of the column for returning mercury discharged from the top of the column, the low pressure tube between the return tube and the connection with the top of the column being unobstructed.
10. 7. An article of manufacture for automatically letting down the vacuum in a discharge tube comprising as a unitary structure a column adapted to receive mercury, a high pressure tube in suitable communication with the bottom of the column, a low pressure tube in communication with the top of the column, and adapted to be connected with the interior of the vacuum discharge tube, and a return tube between the low pressure tube and the bottom of the column for returning mercury discharged from the top of the column, the high pressure tube enclosing the lower portion of the column, and the low pressure tube between the return tube and the connection with the top of the column being unobstructed.
15. 8. An apparatus for periodically varying the vacuum in a sealed tube, comprising in combination, a vacuum pump connected to exhaust the sealed tube, a vertical low-pressure tube connected at its top with the sealed tube by a passage and having an enlarged portion, a shield above the enlarged portion adapted to allow downward passage of any fluid but to prevent liquid from being thrown up into the top portion of the low-pressure tube, a high-pressure chamber, a discharge tube communicating at one end with the enlarged portion of the low-pressure tube, and having its other open end extending downward into said high-pressure chamber, and a capillary return passage from the bottom of the low-pressure tube to the high-pressure chamber which passes at some point below the level of the high-pressure end of said discharge tube, the high-pressure chamber being adapted to retain a liquid at a level above the opening of the discharge tube and to be connected to a closed vessel provided with an adjustable slow leak through which the desired gas may be made to flow.
20. 9. In an apparatus for periodically varying the vacuum in a sealed tube, a vacuum pump connected to exhaust the sealed tube, a low-pressure chamber connected by a passage at its top with the sealed tube, a high-pressure chamber, a discharge tube open at both ends, entering the low-pressure chamber, and having its other end extending downward into the high-pressure chamber, a return passage from the bottom of the low-pressure chamber to the high-pressure chamber which passes at some point below the level of the high-pressure end of the discharge tube, and a closed gas reservoir having communication with the high-pressure chamber, and having an adjustable slow leak through which the desired gas may be made to flow.
25. 10. A periodically-acting vacuum-release valve adapted to be connected between an electrical discharge tube which is continually being exhausted and a partially-exhausted gas chamber into which the gas desired is slowly admitted, comprising a low-pressure chamber, a discharge tube communicating at one end with the low-pressure chamber, a high-pressure chamber communicating with the other end of the discharge tube and connected with a passage adapted to be led into the partially exhausted gas chamber, and a return tube leading from the bottom of the low-pressure chamber to the high-pressure chamber, which passes at some point below the level of the high-pressure end of the discharge tube.
30. 11. A periodically-acting vacuum-release valve adapted to be connected between an electrical discharge tube which is continually being exhausted and a partially exhausted gas chamber into which the desired gas is slowly admitted, comprising a low-pressure tube having communication at its top with the electrical discharge tube, provided with means for preventing liquid from being thrown into its top portion, and having an enlargement below said means, a discharge tube having its lower end open and extending down and its upper end bent over and leading into the low-pressure tube, a high pressure tube surrounding the lower part of the discharge tube and providing a space both above and below the level of the lower end of the discharge tube adapted to hold a liquid, a capillary return tube leading from the lower end of the low-pressure tube to the high-pressure tube and having a portion below the level of the high-pressure tube, and a passage entering the high-pressure tube, having a trap to return a liquid to the high-pressure tube, and adapted to be led into said partially exhausted gas chamber.
35. 12. An apparatus for periodically making hard and letting down the vacuum in an electrical discharge tube, comprising in combination, a vacuum pump connected to exhaust the electrical discharge tube, a low-pressure chamber, a passage having one end opening into the low-pressure chamber, a high-pressure chamber into which the other end of the passage opens, providing space both above and below the level of the opening of said passage thereinto for the retention of a liquid, and another passage adapted to allow a liquid to be retained in the high-pressure chamber, for providing communication between the high-pressure chamber and a partially exhausted vessel into which the desired gas is slowly admitted.
40. 13. In an apparatus for periodically making hard and letting down the vacuum in an electrical discharge tube, a vacuum pump connected to exhaust the electrical discharge tube, high and low pressure chambers, a discharge tube providing communication between the chambers, and a return tube leading from the bottom of the low-pressure chamber to the high-pressure chamber and passing at some point below the level of the opening of the discharge tube into the high-pressure chamber, said high-pressure chamber providing space both above and below the level of the opening of the discharge tube thereinto for retaining a liquid, and communicating with a passage adapted to allow the retention of a liquid in the high-pressure chamber, for connecting the high-pressure chamber with the partially exhausted vessel into which the desired gas is slowly admitted.
45. 14. The process of applying a high voltage across the electrodes in a discharge tube, continuously exhausting the gas from the discharge tube, releasing a substantially fixed quantity of
